UNITED STATES PATENT OFFICE

JOHN LE VALLEY, OF PAINTED POST, NEW YORK, ASSIGNOR TO INGERSOLL-RAND COMPANY, OF JERSEY CITY, NEW JERSEY, A CORPORATION OF NEW JERSEY

UNLOADER FOR COMPRESSORS

Application filed January 21, 1931. Serial No. 510,140.

This invention relates to compressors, but more particularly to an unloader for compressors.

One object of the invention is to minimize 5 the load on the prime mover of the compressor during the starting and stopping periods of the compressor.

Another object is to produce an inexpensive and simplified unloader which may be 10 cheaply maintained and which will be positive in operation.

Other objects will be in part obvious and in part pointed out hereinafter.

In the drawing accompanying the specification and in which similar reference characters refer to similar parts,

Figure 1 is an end elevation, partly in section, of a multiple cylinder compressor and its intercooler having the invention applied 20 thereto, and

Figure 2 is a longitudinal sectional elevation, arranged diagrammatically, of so much of a compressor as will serve to illustrate the invention and a mode of application thereof.

Referring more particularly to the drawing and at first to Figure 1, A designates 25 generally a compressor comprising a base or crank case B upon which are mounted in this instance low and high pressure cylinders C and D respectively.

The cylinders C and D are provided with heads E and F respectively having inlet valves G which may be of any well known type for controlling the admission of fluid 35 into the cylinders. The heads E and F are further provided with discharge valves H through which is expelled the fluid compressed in the cylinders.

In order to reduce the temperature of the 40 medium compressed in the low pressure cylinder C prior to the entry of such air into the high pressure cylinder D the compressor A is provided with an intercooler designated generally by J and comprising a pair of heads K and L connected to the heads E and F respectively, and a series of tubular members O through which the compressed fluid flows 45 from the head K to the head L. The tubular members O are provided exteriorly with fins P to effect rapid radiation of heat from

the compressed medium during its passage through the members O.

The element, such as air or gas about to be compressed, enters the head E through an inlet opening Q into the low pressure cylinder 55 C. After being compressed therein to a higher pressure the fluid passes through the intercooler J and through an inlet opening R in the head F into the high pressure cylinder D. Upon being compressed to the required 60 pressure the fluid passes through the discharge valve H and through an outlet opening S in the head F, whence it may flow to a storage receiver (not shown).

Within the cylinders C and D are the 65 working pistons T and U respectively, each having a connecting rod V operatively connected to the crank pin W of a crank shaft X which is illustrated as being conveniently journaled in the crank case B. The connecting rods V are preferably connected to the same crank pin W so that as one piston approaches the end of its compression stroke the other piston will occupy a corresponding position with respect to the end of its 70 stroke.

In the operation of compressors of this type, and particularly where the compressor is being driven by a prime mover having a low starting torque, it is desirable that the 80 prime mover be relieved of the heavy load resulting from starting the mechanism against compression. In furtherance of this end the apparatus is provided with relief devices adapted to unload the compressor during speeds of operation which are below the 85 normal operating speed, more specifically, during the starting and stopping periods of the compressor. The means provided for

this purpose preferably comprises a conduit 90 Y in the form of a pipe Z which is threaded- 95 ly connected to a casing b secured to the high pressure cylinder D and having a passage c therein to form a continuation of the passage in the pipe Z.

The passage c registers with a passage d in the wall of the cylinder D and said passage d preferably opens into the compression chamber of the cylinder D at a point closely adjacent the head F. The opposite end of 100

the pipe Z may, as illustrated, terminate in a plane which coincides with the longitudinal axis of the crank shaft X. To this end of the pipe Z is threaded a plug e which in 5 turn is threaded into the end of a valve casing f.

The valve casing f may be supported in any suitable and convenient manner, as for instance, by a bracket g on the crank case B 10 and is provided with a chamber h into which extends a projection j of the plug e. The projection j has a bore k wherein is disposed a check valve o, such as a ball, and in the bottom of the bore k is a seat p for the 15 accommodation of the valve o. The plug e is further provided with a passage q where-with the pipe Z communicates. Leading from the passage q and located in the plug e are passages r which communicate at their 20 outer ends with the chamber h. The passages r are so arranged that they will at all times afford communication between the passage q and the chamber h and are therefore 25 in no wise controlled by the valve o.

25 An opposing seat s is provided for the valve o in the valve casing f and leading from the seat s is a passage t which opens into an enlarged bore u also in the valve casing f. A port v in the valve casing f af-fords communication between the bore u 30 and the atmosphere.

Disposed in the bore u and a bore w in the bracket g coincident with the bore u is a guide sleeve x wherein is arranged slidably a 35 pin y which abuts with one end the valve o.

Secured to the end of the crank shaft X adjacent the bracket g, as by means of bolts z, is a guide member 2 having a cylindrical recess 3 to slidably receive a hollow plunger 4. Within the plunger 4 is arranged a 40 spring 5 to act with one end against the plunger and with the other end against the bottom of the recess 3. The spring 5 and the plunger 4 are so arranged that a constant 45 pressure is exerted against the pin y tending to maintain said pin in contact with the valve o during the idle, accelerating and decelerating periods of the compressor A.

To the end that the plunger 4 may be actuated 50 into a position to relieve the valve o of the pressure of the spring 5 a pair of centrifugal weights 6 are mounted on the guide member 2 as by means of pivots 7. The weights 6 are provided with hook portions 8 55 which bear against the outer end of the plunger 4 and thus determine the degree of outward movement of the plunger.

As will be observed, the valve o is remotely located from the cylinder D so that, in the 60 absence of suitable checking devices, the pipe Z would act as a clearance chamber of considerable capacity which would act to lower the efficiency of the compressor. In order 65 therefore to assure maximum output volume of the compressor the casing b is provided

with a valve chamber 9 having opposed seats 10 and 11 to accommodate a ball valve 12 adapted to control communication between the passage c and a passage 13 in the valve casing b and into which the pipe Z opens. 70 The ball valve 12 is reciprocable between the passages 13 and c and leading from the passage 13 to the valve chamber 9 are passages 14 which are located between the ball valve 12 and the pipe Z so that the valve chamber 75 9 may at all times be in full communication with the pipe Z.

The operation of the device is as follows: The medium to be compressed enters the head E through the inlet opening Q, thence flows 80 through the inlet valve G of said head into the cylinder C wherein it is compressed by the piston T and expelled through the discharge valve H into the intercooler J. During the passage of the compressed fluid 85 through the intercooler J the heat resulting from compression is dissipated and the fluid then passes into the cylinder D where it is compressed to a higher value by the piston U and is expelled through the discharge valve 90 H in the head F and through the outlet opening S to its destination.

During this stage of operation, which may be said to be the normal operation, a portion of the fluid compressed in the cylinder D will 95 pass through the passages d, c, the valve chamber 9, the passages 14 and 13 and through the pipe Z into the passage q where it will act against the ball valve o. With the compressor operating at a normal speed 100 the weights 6 will be rocked outwardly by centrifugal force and the hooks 8 associated with the weights 6 will then act against the plunger 4 and depress the spring 5 to such a degree that the pin y may be readily displaced by the pressure of the air acting 105 against the ball valve o so that the ball valve o will seat upon the valve seat s, thus cutting off communication between the cylinder D and the atmosphere.

After the ball valve o reaches this closed position pressure fluid will accumulate in the pipe Z until it reaches a value equal to the maximum value of the fluid compressed in the cylinder D. The pressure fluid thus stored in the pipe Z will then act against the ball valve 12 to maintain said ball valve in the closed position upon its seat 10. In this way only the comparatively short portion 110 of the channel affording communication between the cylinder D and the valve chamber 9 will be exposed to pressure fluid compressed in the cylinder D and the clearance of the cylinder D will therefore be maintained at a minimum, whereas in the absence of a suitable checking device, such as the ball valve 12, the entire channel leading from the cylinder D to the valve chamber 9 would serve as a 115 clearance pocket.

While the compressor is operating at 130

normal speed the weights 6 will render the plunger 4 ineffective to disturb the position of the valve σ . The valve σ will then, as previously stated, occupy its closed position 5 upon the seat s . However, when the compressor is stopped the spring 5 will exert a pressure upon the plunger 4 of sufficient value to overcome the force of the weights 6 and this movement of the plunger 4 will then 10 be transmitted through the pin γ to the valve σ . The valve σ will then be actuated to its other limiting position, that is, against the seat p . The pressure fluid previously stored in the passages between the ball valves 12 and 15 σ will then flow from the valve chamber h through the passages t and v to the atmosphere, thus providing an outlet directly to the atmosphere for any pressure fluid which may remain in the intercooler J and in the 20 cylinder D.

During the subsequent starting period of the compressor the spring 5 exerts a sufficient pressure against the hooks 8 of the weights 6 to prevent said weights from reTRACTING the plunger 4 until the speed of the compressor approaches maximum. The cylinder D will therefore remain in communication with the atmosphere so that any air pumped through the cylinder C and flowing 25 into the cylinder D through the intercooler may find a ready avenue of escape to the atmosphere. As the speed of the compressor is accelerated to a point approaching normal, the weights 6 will retract or depress the 30 plunger 4 to permit the pressure fluid flowing through the pipe Z to again close the ball valve σ .

I claim:

1. An unloader for compressors, comprising a conduit into which pressure flows and having a ball relief valve at one end to communicate the conduit with the atmosphere, said relief valve being held in one limiting position by pressure fluid in the conduit, 40 spring pressed means for actuating the relief valve to another limiting position, centrifugally actuating means for rendering the spring pressed means ineffective to displace the relief valve during the normal operation 45 of the centrifugally operated means, and means near the other end of the conduit for controlling the effective capacity of the conduit.

2. An unloader for compressors, comprising 55 a conduit subjected interiorly to pressure fluid and having a ball relief valve located at one end thereof, said relief valve being held in one limiting position by pressure fluid in the conduit, spring pressed means 60 for actuating the relief valve to another limiting position, centrifugally actuated means for moving the spring pressed means out of contact from the relief valve during the normal operating speed of said centrifugally actuated means, and a check valve at the other

end of the conduit and maintained in closed position by pressure fluid entrapped in the conduit by the valves for controlling the effective capacity of the conduit.

3. A compressor unloader comprising a 70 conduit communicating at one end with the compression chamber of the compressor and communicating with atmosphere, a check valve in said conduit normally held closed by the pressure fluid within said compression chamber for preventing the escape of pressure fluid from said compression chamber, and speed responsive means constructed to hold said check valve open.

4. A compressor unloader comprising a 80 conduit communicating at one end with the compression chamber of the compressor and communicating with atmosphere, a check valve in said conduit normally preventing the escape of pressure fluid from said compression chamber and speed responsive means constructed to hold said check valve open and a second check valve in the conduit 85 relatively close to said compression chamber.

5. A compressor unloader comprising a 90 conduit open to atmosphere and communicating with a chamber in which fluid is compressed, a check valve in said conduit normally held closed by the pressure of fluid within said chamber to prevent escape of pressure fluid therefrom to atmosphere, and speed responsive means constructed to hold said check valve open when the compressor is at rest.

6. A compressor unloader comprising a 100 conduit open to atmosphere and communicating with a chamber in which fluid is compressed, a check valve in said conduit normally preventing the escape of pressure fluid from said chamber to atmosphere, speed responsive means constructed to hold the check valve open when the compressor is at rest, and a second check valve in the conduit relatively close to said chamber.

7. An unloader for compressors, comprising a conduit into which pressure fluid from the compressor may flow, said conduit having an outlet to atmosphere, a valve controlling said outlet and normally actuated by pressure fluid in the conduit to close said outlet, and speed responsive means to actuate said valve to open said outlet when the compressor is at rest and constructed to release said valve to close upon increase of speed.

8. An unloader for compressors, comprising a conduit having an outlet to atmosphere into which pressure fluid from the compressor may flow, a valve normally actuated by pressure fluid in the conduit to close said outlet, and speed responsive means to actuate said valve to open said outlet when the compressor is at rest.

In testimony whereof I have signed this specification.

JOHN LE VALLEY. 130
